UNITED STATES PATENT OFFICE.

FLETCHER AMES, OF BERKELEY, CALIFORNIA.

TENT AND BED.

1,423,171.

Specification of Letters Patent. Patented July 18, 1922.

Application filed May 11, 1921. Serial No. 468,491.

To all whom it may concern:

Be it known that I, FLETCHER AMES, a citizen of the United States, residing at Berkeley, in the county of Alameda and State of California, have invented new and useful Improvements in Tents and Beds, of which the following is a specification.

This invention relates to camp outfits, and particularly pertains to combined tents and beds.

It is a principal object of the present invention to design a tent adapted to use one or more beds, or cots, and which structures serve as suitable anchorage for a tent frame.

The present invention contemplates the use of a cot, the end cross frame members of which are provided with means for detachably receiving vertical and horizontal frame members, over which a tent canvas may be disposed, said members and the cots being readily assembled or knocked down, and thereafter be disposed in a compact bundle for transportation.

The invention is illustrated by way of example in the accompanying drawing, in which—

Fig. 1 is a view in perspective showing one form of the present invention with parts of the tent canvas removed to more clearly disclose the structure;

Fig. 2 is a view in end elevation illustrating a simple form of the device shown in Fig. 1;

Fig. 3 is a view in end elevation showing another form of the present invention.

Referring more particularly to the drawings 10 indicates a cot. In Fig. 1 accommodations are shown for two cots, while in Figs. 2 and 3 a single cot is employed.

These cots are formed with parallel side rails 11 across which a canvas 12 is stretched. The side rails are held in position relative to each other by end rails 13. The length of these rails is sufficient to provide a portion of the rails extending outwardly from the sides of the cot. Pivoted to the side rails 11 are a pair of cross legs 14 which may swing to fold the cot, this, of course, taking place when the end rails 13 have

been removed. Secured to one end of each end rail is a ring member 15 through which a corner post 16 may extend. The lower end of this post is held in a vertical aligned position by a connecting bar 17. This bar is formed with a ring to receive the post and is pivoted to one of the legs of the

cot, as indicated at 18. The opposite end of each of the cross bars 13 carries an extension 19 disposed in longitudinal alignment with the bar and formed with a ring 60 20 at its end. This ring receives a center pole 21. The center pole is rigidly held by a diagonal brace member 22 secured to the end rail 13 and extending upwardly to receive the post. 65

In the form of the invention shown in Fig. 1 where two cots are used, there will be two of the poles 21 spaced a distance from each other to form a doorway at the end of the tent; while in the form of the invention shown in Fig. 2, the short corner post 16 and the long posts 21 will be disposed at opposite sides of the tent and in the corners thereof. The lower ends of the various posts are formed with spikes 23 by 70 which they may be anchored to the ground. The upper ends of the posts are formed with extending pins 24 to receive the ridge poles 25 of the tent. These poles are formed in two pieces of equal length, hinged at their 75 centers by hinge members 26. As the ends of the pole sections abut against each other and the hinges are on the bottom side of the poles, the sections will assume rigid aligned positions when unfolded. The outer 80 ends of these poles have openings to receive the pins 24 of the posts. In the form of the invention shown in Fig. 1, cross bars 27 connect the upper ends of the center posts at each end of the tent. The assembled 85 frame may then be covered with canvas, as shown at 28.

By comparing the structures shown in Figs. 1 and 2, it will be noted that the frame work of the tent disclosed in Fig. 1 merely 90 represents a duplication of the frame and bed structure indicated by dotted lines in Fig. 2, the duplicate structures being connected and held in spaced relation to each other by the bars 27. 100

In the form of the device shown in Fig. 3, a tent of larger capacity is provided while embodying the same inventive idea. In this case, ring bars 29 are secured to one leg of a cot to detachably receive corner posts 30. 105 The other leg of the cot receives a standard 31 having an eye through which a pole 32 extends. Brace members 33 and 34 are provided to receive the lower end of the pole. An adjusting collar 35 is carried by the posts 32 and rests against the brace 34, thus preventing longitudinal movement of the 110

post. A ferrule 36 is provided to permit the posts 32 to be separated into two sections when not in use; and means are also furnished, as indicated at 37, to allow the 5 standard 31 and the braces to be removed from the cot.

In the operation of the present invention it will be assumed that all of the parts are in their "knocked-down" condition, at which 10 time the cots will be folded. To set up the tent of the form shown in Figs. 1 and 2, it is first necessary to unfold the cots and then apply the end members 13 thereto, at which 15 time the bars 17 may be swung outwardly from their pivotal mounting 18 to receive the lower ends of the corner posts 16. These corner posts are passed down through the rings 15 and the eyes of the bars 17. The 20 upper ends of the corner posts are connected by the ridge pole 25. The ring bars 19 are then thrown outwardly to their horizontal positions and the braces 22 are swung upwardly to dispose the eyes of the brace and bar in vertical alignment. The center poles 25 21 are then passed through these eyes and are afterwards connected by the upper ridge pole 25. If a double tent is formed, the 25 duplicate frame and cot sets are connected by the bars 27, after which the frame is covered 30 with tent canvas.

In the form of the invention shown in Fig. 3, the standards 31 are applied to the corners of the cot, after which corner posts 30 are mounted through the eyes of the 35 bars 29, and the supporting posts 32 are passed through the eyes of the standard 31 and the brace 34. The extreme height of the tent may then be regulated by an adjustment of the collar 35.

40 It will thus be seen that the structure here disclosed, while simple in operation and inexpensive, provides desirable folding means for furnishing a tent with cots and a rigid frame structure.

45 While I have shown the preferred form of my invention, it is to be understood that various changes may be made in the combination and structure by those skilled in the art without departing from the spirit of the 50 invention.

Having thus described my invention, what I claim and desire to secure by Letters Patent is:

1. The combination with a cot, a set of upper and lower rigid arms having connection at each outer corner of the cot, one arm of each set being pivoted to the cot, each arm having a rigid ring at its outer end, tent posts passing entirely through the ring members of said sets of arms and engaging the ground at their lower ends and unconnected with the ring members, a foldable ridge pole connecting said posts, another set of upper and lower rigid arms having connection with each inner corner of the cot, the uppermost 60 arm of each second set of arms being pivotally connected to the cot and having a ring member at its outer end, said last mentioned pivoted arms being formed upon a curve, and when extended, being directed upwardly 65 and outwardly with its ring member disposed in vertical alignment with the respective ring member of the respective lower arm, tent posts passing through the ring members of said second sets of arms and unconnected with the ring members and longer than the aforesaid tent posts and at their lower ends engaging the ground, a ridge pole connection between the longer posts, the 70 pivoted arms and their ring members being 75 sustained in extended positions by the posts, and a tent covering for the structure.

2. The combination with a cot, a set of upper and lower rigid arms having connection with the cot at each outer corner of the 80 cot, each arm having a rigid member at its outer end whereby the ring members are spaced from the cot, tent posts passing entirely through the ring members of each set of arms and unconnected therewith, a ridge 85 pole connection between said posts, another set of rigid arms having connection with the cot at each inner corner thereof, one arm of the latter set being pivotally connected to the cot, each arm carrying a rigid ring member at its outer end, tent posts passing through the ring members of each set of arms at each inner corner of the cot and unconnected with the ring members and being longer than the aforesaid tent posts and sustaining the last mentioned pivoted arms in 90 extended operative positions, a ridge pole connection between the longer posts, and a 95 tent covering for the structure.

FLETCHER AMES.
